Daniel G. Gullent

ATTORNEY.

UNITED STATES PATENT OFFICE

1,998,327

INHALANT DEVICE

Clarence Vane McGuire, Detroit, Mich.

Application April 10, 1933, Serial No. 665,322

6 Claims. (Cl. 128—192)

This invention relates to inhalant devices, particularly for the relief of colds, etc.

The principal object of the present invention is to provide an inhalant device which permits the sufferer to inhale fresh, heated air. In the device, means are provided whereby the air may be treated, in passing, by contact with a suitable medicament, preferably of oleaginous nature. Further, the device is provided with means whereby the air may be humidified, in passing, to any desired extent.

More particularly, the device includes a vessel whose air outlet is connected to a face mask by means of a flexible tube or the like, it being intended that the sufferer inhale and exhale through the face mask.

Further objects of the invention will presently appear upon reference to the following detailed description of a preferred embodiment of the same, which embodiment is shown in detail in the appended drawing. In this drawing:

Figure 1 shows the device in section;

Figure 2 is a diagrammatic view of the electrical connections of the same;

Figure 3 is a section as if on line 3—3 of Figure 1;

Figure 4 shows an alternative form of face mask, to small scale.

Referring to the drawing, it will be seen that the device includes a vessel 10 resting upon and preferably frictionally fitted and sealed to a foundation or bottom plate 11 provided with rubber buttons 12, these spacing the bottom of the device from the table or other support upon which the device rests so that air may pass under the device and up through the same, as indicated by the arrows.

The air inlet is in the form of a tube 14 pressed upwardly from the bottom plate 11 and open at its upper end. A seat 15 is formed at the lower end of the tube 14 and in this seat is disposed a heating plate 16 which may be of glazed or unglazed porcelain, and which may be provided with suitable heating coils 17 and 18. It is observed that the heating plate, including its coils, are not specifically new but are of a type that can be purchased in the open market. The heating plate is provided with an aperture 19 therethrough, which permits air from under the bottom 11 to pass through the inlet tube 14.

In the form shown the heating plate 16 is secured in its seat 15 by a bead 20, and the plate may be snapped into its seat past the bead and will be held in its seat by the bead, after the plate has been inserted in its seat.

The upper end of the inlet tube, as above stated, is open and may be covered by a sheet of gauze 21, the latter being removably mounted and held on the upper end of the tube by means of a spring wire 22 whose ends 23 are crossed to permit easy application of the gauze to the upper end of the tube. On the gauze may be poured a suitable medicament of oleaginous or other nature, as desired, to process the air flowing through the inlet tube 14, gobs of the medicament being shown in place on the gauze.

The upper portion of the vessel 10 is open and is provided with a screw threaded cap 24, which may be sealed with respect to the vessel itself, by means of a suitable sealing gasket 25.

Into the lower part of the vessel 10, and to a level below the upper end of the inlet tube 14, may be poured water 26 for humidifying the air flowing through the inlet tube. The water and the oleaginous medicament disposed on the surgical gauze may be introduced into the tank through the open upper end of the same when the cover cap 24 is removed.

Disposed against the side wall of the tank and in the upper portion of the latter, above the level of the water, is a plate 27 bent to form a passage 28, open at the top as at 29, and communicating with an opening 30 having outwardly directed edges, as at 31. The passage 28 and its associated portions constitute an outlet for the tank which is observed draws air from the upper portion of the tank and directs it downwardly to outlet at the lower portion of the tank.

It is observed that it is more desirable to draw air from the top of the tank, where it will have passed through the mixing chamber indicated generally as at 32, and it is also more desirable to have the flexible tube 33 which connects to the outlet flange 31, connected to the tank at the bottom thereof, so that upsetting of the tank is less likely to occur.

The flexible tube 33, which may be of rubber or the like, is of a suitable length as desired and one of its ends is fixed to the flange 31 at the outlet opening 30 of the tank 10. Its other end is fixed to a face mask 38 of pliable material such as rubber, the tube being cemented to a nipple 37 formed from the mask. An opening 38 in the mask communicates the tube with the interior of the mask so that air passing through the tube will be directed to the mouth and nostrils of the sufferer over whose face the mask is placed, it being observed that the edge 39 of the mask is suitably contoured to fit the average face with a relatively close and air tight fit. A valve in

the nature of a rubber flap 41, cemented or otherwise secured to the face mask, is provided to control the opening 38.

The pliable nature of the mask material operates with the contour of line 39 to insure a close, but comfortable fit. This valve opens inwardly on inhalation, and serves to close the opening 39 on exhalation. A second opening in the mask, referenced 44, is provided for exhalation and this opening is controlled by a flap valve 45 secured to the mask in such a fashion as to open outwardly only.

The heating plate coils 17-18 are positioned so that the former heats the air in inlet tube 14 while the latter heats the water 26.

The heating plate 16 and its coils 17-18 are connected by conductors 50, 51, 52, to a suitably mounted switch 53, which in turn is connected to line conductors 54, 55, by a conventional two-conductor cable 56 having a conventional plug 57 on its end. The switch is in the nature of a selector and includes a switch arm 58 adapted to assume anyone of three positions, shown in Figure 2.

When the arm 58 is in position 1, it will not connect any of the heating coils to the line and, therefore, neither the air nor the water in the tank will be heated by the coils.

When the arm is in position 2, the air heating coil will be energized, the water heating coil not being energized. The air in tube 14, being heated, will heat the water to a certain extent. Further, as the air temperature rises, the water will be heated more and more automatically, and this is desirable since a greater air temperature should be accompanied by a greater heating effect on the water. When the arm is in position 3, both coils will be energized and both the air and water will be heated.

In Figure 4, there is shown a face mask 60 which is so constructed that the air valves 61 and 62 thereof, controlling the inlet and outlet openings 63-64, respectively, will operate satisfactorily whether the mask be in horizontal position, as shown, on the face of a prone patient, or in vertical position (90° counterclockwise from Figure 4) on the face of a patient who is sitting or standing. The valves are tapered, so as to be heavier near their free edges than at their secured edges, and tend to close, due to gravity, regardless of the position of the patient, the opening of the valves being in opposition to the influence of gravity. This type of mask is extremely well suited for the use to which it is put.

Further, the mask may be provided with a groove 65 for the reception of an elastic band which holds the mask in place against the face of the patient.

Now having described a preferred embodiment of the invention reference will be had to the following claims which determine the scope of the invention. I claim:

1. In an inhalant device of the character described, a vessel having an aperture in its bottom, a tube surrounding said aperture and projecting upwardly for a distance, to form an air inlet, the vessel being supported on legs which space the bottom from the supporting surface so that air can pass under said bottom to said inlet, liquid on said bottom and between said tube and the vessel side wall, and a heating plate under said bottom and having air heating means in the air inlet path, and an air outlet at the lower part of said vessel, near the bottom, the outlet being connected to the upper interior of the vessel, through a baffle passage.

2. In an inhalant device of the character described, a vessel having an aperture in its bottom, a tube surrounding said aperture and projecting upwardly for a distance, to form an air inlet, the vessel being supported on legs which space the bottom from the supporting surface so that air can pass under said bottom to said inlet, liquid on said bottom and between said tube and the vessel side wall, and a heating plate under said bottom and having air heating means in the air inlet path, and liquid heating means under the liquid, and an air outlet at the lower part of said vessel, near the bottom, the outlet being connected to the upper interior of the vessel, through a baffle passage.

3. In an inhalant device of the character described, a vessel having an aperture in its bottom, a tube surrounding said aperture and projecting upwardly for a distance, to form an air inlet, the vessel being supported on legs which space the bottom from the supporting surface so that air can pass under said bottom to said inlet, liquid on said bottom and between said tube and the vessel side wall, and a heating plate under said bottom and having air heating means in the air inlet path, and an air outlet at the lower part of said vessel, near the bottom, the outlet being connected to the upper interior of the vessel, through a baffle passage.

4. In an inhalant device of the character described, a vessel having an aperture in its bottom, a tube surrounding said aperture and projecting upwardly for a distance, to form an air inlet, the vessel being supported on legs which space the bottom from the supporting surface so that air can pass under said bottom to said inlet, liquid on said bottom and between said tube and the vessel side wall, and a heating plate under said bottom and having air heating means in the air inlet path, and an air outlet at the lower part of said vessel, near the bottom, the outlet being connected to the upper interior of the vessel, through a baffle passage, and a face mask connected to said outlet by a flexible tube.

5. An air inhalant device of the character described including a vessel, air inlet and outlet tubes passing through a wall portion of said vessel adjacent the bottom thereof and terminating at a point considerably above said bottom, air heating means in the air path, a liquid body in said vessel surrounding the air inlet tube and having its upper surface below the upper end of said air inlet tube, and a fabric barrier on the upper end of one of said tubes and thereby interposed in the air path from the inlet to the outlet.

6. An air inhalant device of the character described including a vessel, an air inlet tube passing through a wall portion of said vessel adjacent the bottom thereof and terminating at a point considerably above said bottom, an air outlet, air heating means in the air path, a liquid body in said vessel surrounding the air inlet tube and having its upper surface below the upper end of said air inlet tube, and a fabric barrier interposed in the air path from the inlet to the outlet.

7. An air inhalant device of the character described including a vessel, an air inlet tube passing through a wall portion of said vessel adjacent the bottom thereof and terminating at a point considerably above said bottom, an air outlet, air heating means in the air inlet path, a liquid body in said vessel surrounding the air inlet tube and having its upper surface below the upper end of said air inlet tube, means for heating and vaporizing said liquid body, the space above said liquid body, into which opens the air inlet tube, being a mixing space into which enters heated air and liquid vapors, the air being heated and the liquid being vaporized before the heated air and the liquid vapors enter the mixing chamber and mix.
